UNITED STATES PATENT OFFICE

147,890

DESIGN FOR A FLOOR POLISHER

De Witt Clausen, Akron, Ohio, assignor to Clarke Sanding Machine Company, Muskegon, Mich., a corporation of Michigan

Application August 2, 1946, Serial No. 132,245

Term of patent 14 years

(Cl. D9—2)

To all whom it may concern:

Be it known that I, De Witt Clausen, a citizen of the United States, residing at Akron, in the county of Summit and State of Ohio, have invented a new, original, and ornamental Design for a Floor Polisher of which the following is a specification, reference being had to the accompanying drawings, forming a part thereof.

In the drawings:

Fig. 1 is a perspective view as seen by an observer looking from a point at the front and to the left of the floor polisher, embodying my new design,

Fig. 2 is a perspective view as seen by an observer looking from a point to the rear and right of the floor polisher.

I claim:

The ornamental design for a floor polisher, substantially as shown.

DE WITT CLAUSEN.
